ROLLER BIT

Clyde Brendel, Los Angeles, Calif.

Application July 12, 1938, Serial No. 218,810

14 Claims.

(Cl. 255—71)

This invention relates to a roller bit, and more particularly to a type of bit carrying a plurality of cutters for removing the formation at the bottom of the hole.

It is an object of this invention to provide a roller bit that can be readily assembled, and still be of sturdy construction in its entirety and in its component parts.

Another object of the invention is to simplify the construction and manufacture of roller bits, especially those including cross cutter rollers, which serve to cut the major portion of the bore, and side cutter rollers, which are designed to cut the outer portions of the bore and maintain the hole to gauge.

Another object of the invention is to so arrange and support the cross cutter rollers of a roller bit as to leave substantially no core at the axis of the hole produced.

20 A further object of the invention involves a roller bit having cutters and bearing supporting parts which can be easily assembled to the main body of the bit, and also readily demounted therefrom with substantially no effect upon the main body portion, in order that the cutters, bearings, and bearing supporting parts can be replaced.

Still another object of the invention is to provide a roller bit having cutters that are adjustable to produce various bore hole sizes or diameters.

Another object of the invention is to provide a roller bit having cutters that are adjustable to produce various bore hole sizes or diameters, and in which the cutters are properly locked in their 35 particular positions of adjustment.

The present invention has other objects and advantages which will become apparent from a consideration of one embodiment of the invention, which is shown in the drawing accompanying and forming part of the present specification.

40 Although this particular form will now be described in detail to illustrate the general principles of the invention, it is to be understood that the invention is not limited to the specific details disclosed, but covers all variations, modifications, and adaptations falling within the scope of the appended claims.

In the drawing:

50 Figure 1 is an elevation partly in section of a roller bit embodying the present invention.

Figure 2 is a sectional view of the bit, taken along the plane 2—2 of Figure 1.

55 Figure 3 is an elevation of the bit as seen from the right of Figure 1, and

Figure 4 is a perspective view of the structure used for supporting the cross cutter rollers.

The roller bit includes a main body or shank portion 1 having a tapered threaded pin 2 at its upper end whereby the bit can be rotated from the surface of the bore through the usual drilling string (not shown), or turned by other suitable mechanisms, as a multi-stage hydraulic turbine (not shown) positioned in the drilling string above the bit. The main body portion also carries cross cutter rollers 3, 3' which will remove the major portion 3a of the formation material, and also side cutter rollers, 4, 4' that are adapted to remove the outer portions 4a of the bore diameter and maintain the hole to gauge. These cutters are suitably mounted for rotation about their own respective axes, being provided with appropriately shaped teeth, which in the present instance are of generally V-shape, although it is to be understood that various other shapes and 20 designs of teeth can be used in place of the specific forms disclosed. The side cutter rollers 4, 4' have the back portions 5 of their teeth engageable with the walls of the hole to determine the final diameter of bore produced by the bit. 25 The effective life of each tooth is preferably increased by hardfacing one or more of its cutting surfaces in a well-known manner, as by the use of welded on tungsten carbide.

The cross cutter rollers 3, 3' are carried by a 30 unitary supporting structure 6 having an upper face plate 7 and three depending legs 8, 9, 10. Each of the legs is provided with a bore 11, 12 or 13 through which extends a single bearing supporting shaft 14, suitably held in place by welding material 15 attaching the end portions of the shaft to the sides of the bores 11 and 13 in the end legs 8 and 10 so that the shaft is prevented from rotating and moving axially while the drilling tool is in operation.

40 The shaft 14 serves as an external raceway for a plurality of bearings 16, preferably of the roller type, which contact also with the internal raceways 17, 17 provided in the respective cross cutters 3, 3'. The roller bearing construction described will serve to transmit to the bearing supporting shaft the radial loads imposed by the formation upon the cutters. End thrusts, or axial loads, are transmittable through the respective thrust bearings 18, 18 each of which preferably consists of a ball race 18a bearing against one of the end legs 8 or 10, a second ball race 18b abutting a cross cutter with the thrusts or loads passing from the cross cutters to the end legs 55

through the intermediate balls 18c engageable with both races. Each cross cutter is preferably recessed to receive and encompass its bearing. While substantially the entire end thrust will be directed outwardly through the thrust bearings 18, 18, any inwardly directed end thrusts will be absorbed by the engagement of the inner end portions 19 of the cross cutter rollers with the intermediate leg 9. These portions preferably extend inwardly to the bearing shaft 14 to limit the extent of axial movement of the rollers 16 and confine them in operative position.

Each of the side cutter rollers 4, 4' is mounted upon an arm 20 having a bearing supporting member 21 extending inwardly therefrom. Radial loads are preferably transmitted from the cutter to the bearing support through the rollers 22 moving on the outer cylindrical raceway 23 on the bearing supporting member and the inner cylindrical raceway 24 in the cutter. Outwardly directed end thrusts are transmitted through bearing balls 25 riding in the toric raceway 26 in the end face of the bearing supporting member and in a corresponding raceway 27 provided in each cutter. Each cutter is maintained in assembly on its bearings by means of the pin 28 threadedly or otherwise received in a bore 29 in the arm 20, the pin having a large head 28a bearing against the inner end surface of the cutter and preferably seated within a recess 28b. Assurance is made that the pin will not be removed through the use of welding material 30 fastening its outer threaded end portion to the side walls of the bore 29 in the depending arm. This headed pin, in addition to holding the cutter and bearing parts in assembly, will also resist inwardly directed end thrusts imposed by the sides of the bore upon the side cutters.

The cross cutters 3, 3' can be assembled to their supporting structure 6 by placing the ball and roller bearings 18, 16 in the bores provided in each cutter, and then inserting the cutters containing the bearings between the legs 8, 9, 10 of the supporting structure with the cutter bores in alignment with the holes 11, 12, 13 in the legs. The bearing supporting shaft 14 can then be inserted through the legs and cutter bores beginning with one of the end legs 8 or 10. The welding of the end portions of the shaft as heretofore described will insure that the parts will be held in assembled relationship.

In a similar manner, the rollers and balls 22, 25 can be placed on the respective raceways of the side cutter bearing supporting members 21, 55 and the cutters 4, 4' placed thereover with the rollers and balls engaging the cutter raceways. The headed pins 28 can then be placed through the bores in the cutter and bearing support and screwed to the supporting arm 20, after which 60 the weld 30 can be deposited in the hole 29 in the arm.

After assembling the cutters to their respective supporting structures, such parts are fixed to the main shank body 1 primarily through the use of welded material. The undersurface of the main body is preferably a plane 1a, and the upper surfaces 1a, 20a of the cross cutter supporting plate 7 and the side cutter supporting arms 20 are correspondingly flat or plane so as to contact 65 snugly therewith when the parts are placed together. Such assembly is accomplished by grouping the various supporting members approximately in the relative positions they will occupy when attached to the main body portion. That 70 is, the side cutter supports are disposed approxi- 75

mately at right angles with respect to the cross cutter support. With the flat surfaces 1a, 20a of these parts engageable with the plane surface 1a on the main body portion, the cross cutter supporting structure 6 can be initially secured 5 to the main body portion 1 by means of screws 31 passing through bores 32 in the plate 7 and threadedly received in the bores 33 provided in the main body portion. The heads 34 of the screws will engage with the underside 35 of the plate to 10 hold the parts in assembly.

Adequate securing of the cross cutter supporting member 6 to the main body portion is obtained through beveling or scarfing the plate around its entire perimeter and building up welding material 36 in the groove thus produced between the beveled plate portion and the plane surface 1a of the shank to produce a substantially rigid and integral connection between the shank 1 and the cross cutter supporting structure 20 6. Similarly, the upper portions of the side cutter supporting arms 20 are beveled or scarfed for the deposition of welding material 37 in the groove formed with the shank. This weld will likewise extend almost entirely around the arms. 25

Due to the inclined axis about which the side cutter rollers 4, 4' are rotatable, the inner surface 20b of the arms 20 can be inclined upwardly and inwardly. This arrangement will permit an overlap to be achieved between the cross cutter supporting member and the arms, which overlap can result from the bevel 7b initially formed on the cross cutter plate 7. Additional attachment and integration of the arms and plate can be had by welding in the fillet 38 between the under-surface 35 of the plate and the respective inclined surfaces 20b of the arms 20.

The arms supporting the side cutters 4, 4' can be assembled in various definite positions of adjustment with regard to the main body portion 40 so that the same parts can be used to provide a drilling bit capable of producing a limited range of bore hole sizes or diameters. In the specific form disclosed in the drawing, the upper portion of each arm is provided with a preferably 45 cylindrical recess 39 which can accommodate an eccentric head 40 made integral with, or otherwise secured to, an eccentric shaft 41 which can fit within a hole 42 provided in the main body of the drilling tool. The eccentric 40 is provided with an offset "x" with respect to the center line 50 of the shaft 41. By turning the shaft 41 relative to the arm 20, it is apparent that a range of adjustment or movement of the side cutters 4, 4' transversely of the bit axis can be had equal to 55 twice the distance of the offset, or $2x$. The teeth on the side cutters are of sufficient length to overlap the path 3a traced by the cross cutters, so that the adjustment of the side cutters outwardly to the maximum extent will still leave no 60 gap between the paths traced by the side cutters and cross cutters.

The necessary adjustment for diameter can be made just prior to the welding of the side cutter arms to the main body of the bit simply by turning the eccentric shafts 41, which will effect an inward or outward movement of the arms and cutters until the desired effective bit diameter is obtained. The upper arm portions could then be tacked by welding to hold the adjustment obtained, after which the entire portion around the arms could be welded, as previously described.

However, it is preferred to fix the position of each eccentric 40 within the bore 39 in its co-operating arm prior to assembly of the various 75

parts to the main body portion. To achieve this purpose, the eccentric head is provided with a plurality of circumferentially spaced notches 48a which can seat the conical end of a set screw 43 threaded into a bore 44 provided in the outer face of each arm. The turning of the eccentric to various angular positions in the bore 39 will finally determine the position of the side cutters when the arms 20 are attached to the main shank portion of the bit, and consequently, the bore hole size produced. In the position shown in Figure 1, the eccentric is so adjusted as to provide a minimum bore size diameter, the set screw 43 seating within one of the notches 48a. Prior to assembly of the arm to the shank, if the eccentric were turned 180 degrees and the set screw then inserted in the opposite notch, a maximum bore diameter would be obtained for the particular eccentric throw being used. Turning of the eccentric to various intermediate positions would provide correspondingly intermediate side cutter adjustments and produce intermediate bore diameters. Once the eccentric has been properly positioned in its bore and held in position by the set screw, the particular side cutter supporting arm, eccentric, and eccentric shaft can be assembled to the shank by placing the shaft within the shank hole 42 and welding the arm 20 to the main body 1 as described. If deemed essential, removal of each set screw can be prevented by welding its head to the arm 20.

It is the desirability of providing the overlapping relationship and eccentric side cutter mounting which requires that the various supporting parts for the cutters be placed against the plane surface of the shank in substantially their proper assembled relationship prior to the building up of the welded material in the grooves between the shank 1, plate 7, and upper supporting arm portions. Otherwise, the need for inserting the eccentric shafts into the shank bores would conflict with the requirement that the inclined arm faces 20b be overlapped by the bevels 'b on the plate 7.

Although not essential to the maintenance of the side cutters in adjusted position, the upper end of the eccentric shaft 41 is preferably fixed with respect to the main body of the bit. Attachment can be made simply by welding the end of the shaft to the sides of the bore 42 which receives it. However, it is preferred to use the welded arrangement now to be described.

It is customary to provide roller bits with reamer cutters 45 on the tapered portions 46 extending between the upper pin 2 and the outermost body portions, in order that the bit can drill its way out in the event the formation caves into the hole being produced. In the present instance, the reamer blade 45 is designed to function as a lock for the eccentric shaft in addition to its ordinary function. This purpose is achieved by providing a blade having the usual outer cutting edges with its inner portion 45a stepped to fit within the bore 42 receiving the eccentric shaft 1 and in close proximity or engageable with the upper end of this shaft. The reamer blade is suitably scarfed or beveled, built up welding material rigidly integrating it with the main body of the bit and also with the eccentric shaft. The welded attachment between the shaft and reamer blade not only serves to lock the eccentric shaft in adjusted position, but also aids in the support of the side cutter arms, acting through the set screw 43. Since two eccentric shafts are used, at least two reamer blades can be provided on op-

posite sides of the bit, although this member can be increased.

The drilling tool is kept clean and the cuttings removed from the bottom of the hole by circulating fluid through the drilling string (not shown) and then through the passageway 47 provided in the main body of the bit. The cross cutter support 7 is provided with two flaring discharge nozzles 48, 49 communicating with the passageway to direct drilling mud or other fluid onto the cross cutters to clean them of adhering matter. The side cutters are kept clean by fluid discharging through the holes 49, 49 in the cross cutter support, which holes communicate likewise with the internal passageway 47 in the main body of the bit.

To eliminate the core that usually remains at the axis of the bore, the intermediate depending leg 9 is offset to one side of the center line of the bit so that one of the cross cutters 3 can extend to the hole axis. In performing its cutting action on the bottom of the hole this cutter will insure that the central portion of the bore material is removed by its cutting teeth, rather than requiring it to be broken away by non-cutting portions of the bit. Drilling progress of the tool is thereby increased.

The bit structure described can have its cutting elements replaced, eliminating the need for discarding the entire tool after a run has been made. Only those parts need be eliminated that are worn. As it is usual for the main body portion 1 to receive practically no wear during use of the bit, it can be used for a number of runs. In the instant case, the various welds 36, 37 integrating the cross cutter support and side cutter arms with the main body of the bit can be burned away through the use of a suitable cutting torch or carbon pencil. Similar cutting away of the welds binding the eccentric shafts 41 to the reamer cutters 45 and removal of the screws 31 holding the plate to the shank will permit the entire lower portion of the bit to be removed from the main body portion 1. In removing the welds, substantially no damage is done to the main body portion, permitting its use with another assembly at a savings in material and expense.

Usually, the cross cutter support 6 and the side cutter arms 20 can be used over again, their respective cutters 3, 3', 4, 4' being easily replaceable. The side cutters can be removed by burning away the weld 38 or by drilling it out on a suitable drill press. The threaded pin 28 can then be unscrewed to allow removal of the side cutter and its replacement by a new one, the pin then being reinserted and rewelded to the arm. In a similar manner, the welds 15 at the ends of the cross cutter main bearing shaft 14 can be burned away or drilled out, allowing this shaft to be moved endwise from the cross cutter support and the cutters taken from their positions between the depending legs. A set of new cross cutters, and also roller and ball bearings, if necessary, can be placed between the legs, the main bearing shaft reinserted and rewelded, as previously described.

I claim:

1. A drill bit including a main body having a single plane surface at its lower end, a unitary supporting structure having a plane surface contiguous said main body surface, and a plurality of depending legs, an arm on each side of said structure, each arm having a plane surface contiguous said main body surface, means for securing said structure and arms to said main body in the

70

region of said contiguous surfaces, and roller cutters rotatably carried by said legs and arms.

- 5 2. A drill bit including a main body having a single plane surface at its lower end, a supporting structure having a plane surface contiguous said main body surface, an arm at each side of said structure the inner faces of said arms being overlapped by said structure which extends beyond the ends of said inner faces, each arm 10 having a plane surface contiguous said main body surface, said structure and arms being welded to said main body in the region of said contiguous surfaces, and roller cutters rotatably carried by said structure and arms.

- 15 3. A drill bit as defined in claim 2; the overlapping portions of said structure and arms being welded together.

- 20 4. A drill bit including a main body, a supporting structure welded to said body, an arm on each side of said structure welded to said body, each arm having an inner surface inclined upwardly and inwardly, said structure overlapping and engaging the inclined arm surfaces, and roller cutters rotatably carried by said structure 25 and arms.

- 30 5. A drill bit including a main body having a plane surface at its lower end, a unitary supporting structure having a plane surface contiguous said main body surface, an arm on each side of said structure, each arm having a plane surface contiguous said main body surface, means for securing said structure and arms to said main body in the region of said contiguous surfaces, said structure including a plurality of depending 35 legs, cross cutter rollers rotatably carried by said legs, and side cutter rollers rotatably carried by said arms.

- 40 6. A drill bit including a main body having a plane surface at its lower end, a supporting structure having a plane surface contiguous said main body surface, an arm on each side of said structure, each arm having a plane surface contiguous said main body surface, means for securing said structure and arms to said main body 45 in the region of said contiguous surfaces, said structure including a pair of depending end legs and an intermediate leg, a pair of cross cutter rollers each rotatably carried between an end leg and said intermediate leg, and roller cutters rotatably carried by said arms.

- 50 7. A drill bit as defined in claim 6, said intermediate leg being offset with respect to the axis of the bit, whereby one of said cross cutter rollers can extend to said axis.

- 55 8. A drill bit including a main body, a supporting structure attached thereto, said structure having a pair of depending end legs and an intermediate leg, a roller cutter rotatably mounted between and carried by each end leg and said intermediate leg, said intermediate leg being offset with respect to the axis of the bit, whereby one of said cutters can extend to said axis.

9. A drill bit including a main body, a support attached thereto, a roller cutter rotatably carried by said support, and adjustable means within said support and cooperable with said body, said adjustable means being movable to various positions of adjustment while retained in said support, whereby the generally radial position of said support with respect to said body can be varied.

10. A drill bit including a main body, a support attached thereto, a roller cutter rotatably carried by said support, adjustable eccentric means within said support, a shaft within said body fixed to said eccentric means, and means for locking said eccentric means and shaft in various positions of adjustment.

11. A drill bit including a main body, a support attached thereto, a roller cutter rotatably carried by said support, adjustable eccentric means mounted within said support and adapted to be turned therewith, a shaft within said body fixed to said eccentric means, and means for locking said eccentric means and shaft in various positions of adjustment.

12. A drill bit including a main body having a plane surface at its lower end, a support having a plane surface contiguous said main body surface, said support being welded to said main body in the region of said surfaces, a roller cutter rotatably mounted on said support, an eccentric within said support, a shaft within a bore in said body fixed to said eccentric, and means for locking said eccentric and shaft in various positions of adjustment to determine the position of said support with respect to said body.

13. A drill bit including a main body, a support attached thereto, a roller cutter rotatably carried by said support, adjustable eccentric means within said support, a shaft within said body fixed to said eccentric means, and a reamer fixed to said body and shaft to lock said eccentric means in selected positions of adjustment.

14. A drill bit including a main body having a single plane surface at its lower end, a supporting structure having a plane surface contiguous said main body surface, an arm on each side of said structure, each arm having a plane surface contiguous said main body surface, said structure and arms being welded to said main body in the region of said surfaces, said structure including a plurality of depending legs, cross cutter rollers rotatably carried by said legs, side cutter rollers rotatably carried by said arms, an eccentric within each arm, a shaft fixed to each eccentric, each shaft fitting within said main body, said eccentrics being adjustable whereby the transverse positions of said side cutter rollers can be varied.

CLYDE BRENDEL.
